(57) **CLAIM**

The ornamental design for a wireless entrance communication device, as shown and described.

DESCRIPTION

FIG. 1 is a front, left, top perspective view of a wireless entrance communication device;

FIG. 2 is a front elevation view thereof;

FIG. 3 is a rear elevation view thereof;

FIG. 4 is a left-side elevation view thereof, the right-side elevational view being a mirror image of the left-side elevation view;

FIG. 5 is a top plan view thereof; and,

FIG. 6 is a bottom plan view thereof.

The dashed broken lines depict portions of the wireless entrance communication device that form no part of the claimed design. The dot-dash broken line represents a boundary of the claimed wireless entrance communication device which forms no part of the claimed design. The claimed design extends to the dot-dash broken line boundaries in the figures but does not include the boundary.
